UNITED STATES PATENT OFFICE.

EDWARD E. HINRICHSEN, OF NEW YORK, N. Y., ASSIGNOR, BY MESNE ASSIGNMENTS, TO WESTERN ELECTRIC COMPANY, INCORPORATED, A CORPORATION OF NEW YORK.

SEMI AUTOMATIC TELEPHONE SYSTEM.

Application filed February 27, 1925. Serial No. 11,960.

This invention relates to telephone exchange systems and particularly to systems in which connections are established in part by operators and in part by machine switching apparatus.

The object of the invention is to improve the organization of selecting and controlling mechanism in a system of the foregoing character where trunks leading from an operator's position to automatic switches are identified to the operator for use.

A feature of the invention relates to a system in which an operator by setting up a designation on her keyboard causes an idle 15 sender and an idle marker to become associated with such position, each receiving therefrom a separate portion of said designation, the marker serving to select an idle outgoing trunk and to cause an indication 20 thereof to the operator and the sender serving to control switches or other responsive mechanism at the distant end of such trunk.

Another feature relates to a sender for use in a system of this character which is 25 adapted to control switches of the power driven type by revertive impulses or to send direct code impulses to control switches of the coordinate type in the distant office.

A further feature resides in the means for 30 translating the numbering of the trunks as they appear on the selector frame vertical into the numbering of the corresponding trunks as they appear in the multiple at the operator's position.

Other and further features contemplated 35 by the present invention will be more clearly understood from the following detailed description and from the appended claims.

Referring to the drawing, Figs. 1 to 13, 40 taken in the order shown in Fig. 14, illustrate a system embodying the principles of this invention.

Fig. 1 shows the key equipment at the operator's position.

Fig. 2 illustrates a position finder switch 45 of the coordinate type which serves to connect an idle sender with the key set of an operator's position.

Fig. 3 shows the position connector circuit which is employed herein to connect an 50 idle marker with the operator's key set.

Fig. 4 discloses the marker translating circuit which is provided for translating the

office code to determine in response to the office code transmitted, the class of trunks 55 necessary for the completion of the call and for connecting a desired trunk group in such class extending to the desired office.

Fig. 5 represents the marker selection circuit in which the marker selects an idle trunk 60 and holds it in readiness for connection. This figure also represents the means for translating the number of the seized trunk on the selector frame vertical into the numbering of the corresponding trunk jack that 65 appears in the trunk multiple at the operator's position.

Fig. 6 illustrates the trunk indicator at the operator's position, which displays the number of the seized trunk as it appears in 70 the multiple.

Fig. 7 discloses the trunk and frame connectors which serve to connect the marker with the selector switch frame in which 75 appears the desired group and to switch such group for testing.

Fig. 8 shows a sender connector circuit and the office code registers of the sender. This figure also shows the trunk group equipment which is provided for the purpose of holding 80 the desired group of trunks busy until the marker has completed its operations and is released.

Fig. 9 illustrates the sender numerical registers which are connected through the 85 position finder switch shown in Fig. 2 with the numerical keys in the operator's position.

Fig. 10 shows the selector switch of the coordinate type, at which the outgoing trunks terminate. This figure also shows 90 a relative arrangement of the calling subscriber's station, the operator's cord and the outgoing trunk jacks, also the incoming and the final frames of the coordinate type, and the incoming and the final selectors of the 95 panel type in the terminating offices and a called subscriber's station of each.

Fig. 11 discloses the impulsing circuits in which the class of call circuit, established by the translator relays shown in Fig. 4, connects the necessary apparatus and controls the transmission of the necessary impulses for the proper completion of the call.

Fig. 12 shows the panel revertive pulse-counting circuit for calls direct to a panel 105 type office.

Fig. 13 illustrates the panel register circuit.

Fig. 14 represents a diagrammatical arrangement of the various figures of the drawings in their relative positions.

Fig. 15 is a diagram showing the general arrangement of the various major pieces of apparatus required and shows the relation which the various pieces of apparatus bear to one another. The specific control circuits have been omitted but it is believed that an understanding of the general plan of operation of the system may be understood from the following description.

Referring first to Fig. 15, a subscriber's line connected with a station 1501 enters the exchange and has its appearance in an answering jack 1521 at an operator's position 1503. The operator by means of one of her position cords as 1502 connects her head set (not shown) with the subscriber's station, inquires for the number of the called subscriber's line and sets up the call accordingly on her position key set. The operation of the keys for the office designation effects the operation of a position connector 1504 which is individual to position 1503, to seize an idle marker of the group represented by 1506 and 1507. A position finder switch 1508 which is common to a plurality of positions is also operated to connect an idle sender of a group represented by 1509 and 1510. The seizure of the marker effects the operation of a sender-connector 1511 which inter-connects the seized marker and seized sender. The marker is arranged to receive the office code designation and to make the necessary translation thereof for the purpose of determining the class of trunks required for the completion of the call, and selecting a group of trunks in said class which extend to the desired office, and is further arranged to operate a trunk connector 1512 and a frame connector 1513 so as to connect itself with the selected group of trunks and to a trunk selector frame 1514 at which the selected group terminates. The testing equipment in the marker tests the said group of trunks for busy conditions and when an idle trunk is found its associated operating mechanism at the selector frame is actuated to connect the seized sender with the idle trunk. The marker is also arranged to translate the position number of the seized idle trunk at the selector frame into its corresponding position number as it appears at the operator's position and to display the latter number at the trunk indicator. The sender is arranged to receive the numerical designation over the operated contacts of the position finder switch and to transmit the necessary impulses over the seized trunk. In response to these impulses, the apparatus in a distant office, such as 1519 or 1520, which are re-

spectively representative of the panel or the coordinate machine switching type, is actuated to connect the called subscriber's line to the seized trunk. Trunks 1515 and 1516 represent a group of trunks extending to office 1519, and trunks 1517 and 1518 represent a group which extends to an office 1520. Other groups may extend to other types of offices. Each of the outgoing trunks also terminates in a jack such as 1521, 1522, etc., at the operator's position and when the number of the seized trunk is displayed at the indicator, the operator by means of the free end of cord 1502 connects the calling subscriber's line with the seized trunk. When the operator connects the cord 1502 to the jack which is associated with the seized trunk, and the apparatus at the distant office has completed its operation, a connection is established between the calling and called subscriber's lines.

In the case of an office equipped with switches of the coordinate type the senders 1509, 1510 are arranged to send code impulses to a sender such as 1530 at the distant office, which through the agency of a marker as 1531 controls the switches. For further details in this method of operation reference is made to the application of S. B. Williams and E. S. Gibson, Serial No. 645-011, filed June 13, 1923, Patent No. 1,543,967, issued June 30, 1925. Also the senders 1509, 1510 etc, are designed to control call indicators at distant offices as shown in the patent to S. B. Williams No. 1,517,331 granted December 2, 1924.

General description of the system and apparatus.

Referring first to Fig. 10, the receiver at the subscriber's station is removed from the hook and the lamp associated with the subscriber's answering jack at the operator's position lights, indicating to the operator that a connection is desired. The operator inserts the calling end of one of the position cords into the answering jack and receives the number of the called party. Referring now to Fig. 1, the operator depresses the office code keys corresponding to the code of the office in which the called party's line terminates, or an individual office key if one is provided for the desired office, and a start circuit is closed, thereby effecting the seizure of an idle sender and an idle marker. The seized sender is connected to the numerical keys of the calling position by a position finder switch of the coordinate type, and is also connected to the seized marker by means of a relay or a group of relays. At the same time the position is connected direct to the marker by means of a multi-contact relay. Simultaneously the position is connected direct to the marker by means of another multi-contact relay which also estab-

lishes circuits for transferring the office code registration to the marker and for operating the position trunk indicator in accordance with the trunk selected. The marker makes the necessary translation of the office code and tests the corresponding group of outgoing trunks, and connects the first idle one to the sender, the connection being established through a switch frame of the coordinate type.

The testing apparatus in the marker operates a set of translating relays, which in turn operate relays in the position trunk indicator. The operation of the latter relays lights the proper lamps to indicate the number of the trunk. The test relay operated at the selection of any trunk depends, of course, on the position of that trunk on the selector vertical, and this position does not bear any fixed relation to the number of the multiple jack to which the trunk is connected. In fact, if the trunks are multiplied, as would be the case of small groups, the circuits must be so arranged that the same indication will be given for any particular trunk, no matter in which of its positions at the coordinate frame connection is made. This is taken care of by connecting the contacts of the test relays to the translating relays through contacts of the relays which connect the testing apparatus to the trunk group. Cross-connection facilities are provided so that the selection of any trunk in any group will cause the display of the proper number without requiring a definite or fixed relation between the position of the trunk at the selector frame and its number in the operator's multiple. The marker is also arranged to transmit a class indication to the sender and to register the office code in the sender in case the system is used in connection with tandem trunks.

As soon as the marker has found an idle trunk in the desired group and connected it to the sender, and has caused the display of the trunk number on the position trunk indicator, it is released so as to be ready for other connections. The number of the desired line is set up on a single set of numerical keys by the operator and registered on relays in the sender. Four wires, however, are used for operating the register relays, and the circuits are so arranged that no marginal features are involved. As soon as the number has been set up, the sender proceeds to send out impulses over the trunk to operate the distant switches.

The sender in the system shown is arranged to control calls of the following classes:

1. Direct to the panel type central offices.
2. Direct to call indicator equipments in manually operated offices and in both coordinate and panel machine switching offices, having incoming senders.

3. Direct to a tandem office where the complete subscriber's number is recorded in a tandem sender.

4. Direct to a tandem office where the office code only is recorded in the tandem sender and the numerical code is recorded in and sent by the sender in the originating office to control the switching at the terminating office.

As soon as the operator plugs into the trunk jack whose number is displayed, the indicator lamps are extinguished, the connection between a position equipment and the sender is broken down, and the position equipment is restored to normal. The sender remains connected to a trunk until it has finished setting up the connection. It then causes the trunk conductors to be closed through to the multiple jack and releases. In case the sender finishes its work before the operator plugs in, it holds the trunk until it is taken up in the multiple, and then immediately completes it, and releases.

The coordinate switches shown in this system may be of the construction such as described in the patent to S. B. Williams, No. 1,517,331 issued December 2, 1924.

Detail description of the operation.

It is assumed that the subscriber at station 1021, whose line terminates in an office equipped with a key indicator system, desires to hold a conversation with a subscriber in a distant office, whose line number, including the office code designation, is 997-1236. It is also assumed that the called subscriber's line may terminate in any of the offices to which calls of the above enumerated classes can be completed. Although no mention is made of a call being completed through a step-by-step office, this system can be readily adapted to establish the connection for such a call with very few minor changes in the circuits.

When the operator has received the number of the called subscriber, the call is set up on keys which are common to the operator's position by depressing, first, the keys corresponding to the code of the particular office in which the desired line terminates, which in this case, for illustration, will be 9, 9 and 7 shown in Fig. 1 in the rows A, B and C respectively, and second the numerical keys 1, 2, 3 and 6 corresponding to the numerical designation of the called subscriber's line shown in row D. However, the depressing of the numerical keys is not done until the operator has received the usual signals informing her that an idle sender is seized. The operation of keys 9, 9 and 7 close obvious operating circuits for their respectively and individually associated relays 119, 129 and 137. These relays operated and locked in parallel circuits extending through the windings of relays 141, 142 and

143 respectively, common conductor 156, inner right normal contact of relay 149, to ground at the right armature of relay 144, but because of the shunt existing in the 5 original operating circuit for relays 119, 129 and 137 the locking circuits are ineffective to cause the operation of relays 141, 142 and 143. When the keys are released and the shunt circuit is opened relays 141, 10 142 and 143 which are common to their respective rows of keys A, B and C, operate. Should, at this time when relays 141, 142 and 143 are operated, the operator in error depress a second key in any row a circuit 15 would be closed through the winding of relay 146 and this relay would operate. The operation of relay 146 would cause the operation of wipe-out relay 144, and relays 119, 129 and 137 together with relays 141, 142 20 and 143 would subsequently release thereby wiping out all the connections already established and the operator would now proceed with a new set-up. A key 157 is also provided at each operator's position for the 25 purpose of wiping out the connection if she should desire to do so, the relay 144 being operated in this case also to effect the disconnection.

In large multi-office areas the operators' 30 positions are also equipped with individual office keys such as 101 and 102, one key being provided for each of those offices to which the traffic is heavy.

When the relays 141, 142 and 143 operate 35 they close at their upper contacts an obvious operating circuit for the start relay 145.

Relay 145 operates and closes at its inner contact an operating circuit for the no-trunk lamp 601, the circuit being traceable 40 from battery, through the lamp 601, right and left back contacts of relay 602, conductor 603, to ground at the inner armature of relay 145. Lamp 601 which is individual to the operator's position, lights indicating 45 that the start circuit is functioning to connect an idle trunk with the operator's position. At the middle contact of relay 145 a circuit is closed to operate the sender lamp 147, the circuit being traceable from ground 50 at the middle armature of relay 145, outer left back contact of relay 148, inner left back contact of relay 149, right back contact of relay 148, through the lamp 147, to battery. The lamp 147 lights indicating 55 that the start circuit is seeking an idle sender. Also at the middle contact of relay 145 an operating circuit for the vertical group relay 201 of the position finder switch 60 is closed and is parallel to the circuit, just traced, up to the inner left back contact of relay 149 at which point the circuit for relay 201 extends over the outer left back contact of relay 149, conductor 150, upper winding of relay 201, to battery at 65 the outer right armature of relay 203. Re-

lay 201 operates and locks in a circuit extending through its lower winding and front contact, lower back contact of relay 202, conductor 250, through the winding of relay 203 to battery, and relay 203 operates. 70 Relay 201 is common to all the operators' positions on one vertical and in this case, it is assumed to serve position No. 1 together with its associated vertical magnet 204 as described below, to prepare the connection of position No. 1 with the position finder switch through the operation of the first vertical group of contact sets 221 to 227 inclusive. Relay 202 is likewise common to a group of operators' positions and operates similarly to cause the second vertical group of contact sets to prepare a connection between a position in its respective group and the position finder switch. Relay 203 is common to all the vertical group relays on the switch, which are associated with the operator's position, and provides the means for closing the operating circuits for the vertical magnets which operate the groups of contact sets. Should relays 201 and 202 85 operate simultaneously, relay 202 would be the only relay of the two able to lock inasmuch as the original operating circuit for relay 202 would cause a break in the locking circuit for relay 201. The subsequent operation of relay 203 caused by the locking circuit for relay 202 would open the original operating circuit for relay 201 causing it to 90 release and await the deenergization of relay 202 whose period of energization, as 95 will be seen, is very short.

Assuming position 1 to be the only position transmitting a call, the operation of relay 203 closes at the inner left armature an operating circuit for relay 301 which 100 operates, thereby connecting the associated marker No. 1 to the position, the circuit being traceable from ground, at the outer left armature of relay 203, contact of relay 209, conductor 214, upper back contact of 105 relay 215 of the advance marker circuit, conductor 217, through the winding of relay 301, to battery. Relay 301 operates and at the next to its uppermost contact ground is connected to conductor 320 to close an 110 operating circuit for relay 503. Relay 503 115 operates and locks in a circuit extending over its inner right front contact, outer left back contact of relay 502, left back contact of relay 506 to ground. The operation of relay 503 closes an operating circuit for 120 advance marker relay 215, the circuit being traceable from battery, through the upper winding of relay 215, conductors 218 and 505, to ground at the inner left armature of relay 503. Relay 215 operates and opens the 125 original operating circuit for relay 301, but relay 301 remains operated in its locking circuit extending through the winding of relay 209, which up to this time was shunted 130

and is now permitted to operate. Relay 203 operates and prevents relay 322 from operating, which, if permitted to operate at this time would engage a second marker.

5 When relay 503 operates it closes an operating circuit for timing relay 541 which in conjunction with interrupter 542, lamp 543 and relay 506 comprise a timing device employed for the purpose of setting a time 70 limit for automatically holding the equipment engaged, if for some reason the call should be delayed or abandoned. When the time limit expires relay 506 operates and effects the operation of release relay 502 75 which releases the equipment.

Should marker No. 1 be busy relay 215 would be in an operated condition and the operating circuit would now be traced from ground at the inner left armature of relay 203, over the upper front contact of relay 215, upper back contact of relay 216, through the winding of relay 322, to battery and relay 322 would operate connecting marker 2 to the position. But assuming marker 1 to be 80 idle, relay 301 operates and closes a locking circuit for itself over conductor 323, through the winding of relay 209, to ground at the outer left armature of relay 203.

When relay 203 operated it opened the 85 original operating circuit for relay 201 but the latter relay is maintained in an operated position over its locking circuit. At the inner right armature of relay 203 an operating circuit for the position vertical magnet 204 was closed, the circuit being traceable 90 from ground at the inner right armature of relay 203, outer upper contact of relay 201, through the winding of magnet 204, to battery. At the outer left armature of relay 203 an operating circuit for the sender vertical magnet 207 also was closed and this 95 circuit is traceable from ground at the inner left armature of relay 203, contact of relay 213, conductor 210, back contact of relay 211, through the winding of magnet 207, to battery. The closing of the operating 100 circuits for the magnets 204 and 207 of the position finder switch 200 causes both magnets to operate thereby preparing their respective vertical contact groups for connection, magnet 204, as above stated, preparing to connect position 1, and magnet 207 preparing to connect its associated sender with the position. When magnet 207 105 operates it locks in a circuit extending over conductor 266, through the winding of relay 213 to ground at the inner left armature of relay 203, but like relay 209 in the circuit hereinbefore traced, relay 213 does 110 not operate at this time on account of being shunted by the original operating circuit for magnet 207. Should magnet 207 be in an operated condition when the call from 115 position 1 is transmitted, relay 211 of the advance starter circuit would also be in an

operated condition and the circuit closed at the outer left armature of relay 203 to operate a secondary vertical magnet would, therefore, be traced through the upper front contact of relay 211, back contact of relay 212, through the winding of magnet 208, to battery and the sender associated with magnet 208 would be reserved for this call. However, it is assumed that the sender associated with vertical magnet 207 is idle. 120

The operation of magnet 207 closes an operating circuit for sender connector relays 801, 802, 803 and 804, and the circuit may be traced from ground at the lower armature of magnet 207, conductor 233, uppermost operated contacts of relay 301, conductor 302, through the windings of relays 801, 802, 803 and 804 in parallel, to battery. The sender connector relays operate and lock in a circuit extending over conductor 507 to ground at the middle left contact of relay 503. The operations of relays 801, 802, 803 and 804 connect the sender which is now connected through the operated contacts of position finder switch 200 to the operator's position, with the seized idle marker for the purpose of receiving the designation of the desired office. 125

Relay 203 also closed an operating circuit for the horizontal group relay 151, the circuit being traceable from ground at the inner right armature of relay 203, inner upper contact of relay 201, conductor 152, outer contact of relay 145, outer right back contact of relay 149, through the winding of relay 151, to battery. Relay 151 operates and closes at its inner contact an operating circuit for relay 234 which controls the operation of the links 246, 247, etc., of the first group at position finder switch 200, the circuit being traceable from ground at the inner contact of relay 151, conductor 138, through the right hand winding of relay 234, to battery at the left armature of relay 236. Relay 234 operates and locks in a circuit extending over its left-hand winding, through the winding of relay 236, to battery. Relay 236 operates and opens at its left armature the original operating circuit for relay 234. Should it be attempted from a second operator's position to establish a connection through a second group of links, such as 248, 249, etc., while relay 234 is in an operated condition, the operating circuit for relay 235 which is associated with the second operator's position, is prevented from being established by the operated condition of relay 236. As will be seen from the drawing relay 236 is common to relays 234, 235, etc., which control the respective groups of links at position finder switch 200. 130

Relay 236 closes an operating circuit for relay 305 through the lowermost operated contacts of relay 301, conductor 303, outer

contact of relay 151, conductor 237, inner right contact of relay 234, right contact of relay 236, to ground at the armature of magnet 204. Relay 305 operates and connects marker No. 1 for a second purpose, that is, that the marker may receive the office code designation and select a trunk accordingly in the desired group. Relay 236 also closes at its right contact, an operating 10 circuit for horizontal magnet 239, the circuit being traceable from ground at the contact of magnet 204, right contact of relay 236, outer right contact of relay 234, conductor 238, right back contact of relay 240, 15 through the left hand winding of magnet 239, to battery. Magnet 239 operates and completes the connection between its associated link 247 and the operated contact sets 223 and 254 which were prepared for 20 connection by the operation of primary and secondary magnets 204 and 207, respectively. When magnet 239 operates and the associated link 247 is connected to the vertical contact sets 223 and 254 a circuit extending 25 through the relays 153 and 708 is closed, the circuit being traceable from battery, through the winding of relay 153, left contact of relay 144, inner left back contact of relay 148, conductor 244, operated contact 30 sets 223 and 254, conductor 710, through the left hand high resistance winding of relay 708, conductor 902, to ground at relay 944. Relay 708 operates but relay 153 being marginal does not operate in this circuit inasmuch as the circuit extends through the 35 high resistance winding of relay 708. The operation of relay 708 closes a holding circuit for magnet 239, the circuit being traceable from battery, through both windings 40 in series of magnet 239, right hand winding of relay 240, conductor 260 of link 247, lowermost contact of set 254, conductor 709, to ground at the inner left contact of relay 708. Relay 240 operates and opens at its 45 right back contact the original operating circuit for magnet 239. Relay 708 also closes an operating circuit for advance start relay 211, the circuit being traceable from battery, through the winding of relay 211, conductor 709, to ground at the inner left contact of relay 708. Relay 211 operates but does not lock as yet inasmuch as the locking 50 circuit is open at the contact of relay 213. The operation of relay 211 indicates that the associated sender is engaged and prepares an operating circuit for magnet 208 which is associated with another sender. Magnet 239 is now held operated in the 55 circuit traced above, extending through the right hand winding of relay 240 and over the test conductor 260. When relay 240 operates it closes a locking circuit for itself through its left hand winding and left contact to ground at the right armature of relay 261. Should it be desirous to establish 60

a second call through the group of links controlled by relay 234 while the first link in such group is busy, the circuit coming in over conductor 238 would lead over the right front contact of horizontal relay 240, 70 through the left hand winding of magnet 262, and magnet 262 would operate causing in turn the operation of link 246 and horizontal relay 263. Should all the links in this group be busy their associated relays, 75 such as 240, 263, etc., would be in an operated condition and the call would be delayed until a link is available. When an idle line becomes available its associated relay, such as 240, 263 etc., is deenergized 80 by the opening of the relay holding circuit extending over conductor 265, left contact of relay 261, through the winding of relay 264 to battery. Relay 264 will operate and close at its inner right contact an operating 85 circuit for relay 261 which operates and opens at its left contact the holding circuits and at its right contact the locking circuits for the relays 240, 263 etc. When relay 264 operates it substitutes a ground for the locking circuits of the horizontal relays, but through the operation of relay 261 and the subsequent release of relay 264 the substitute ground is also disconnected and the relays that are associated with idle links are, 90 therefore, deenergized and the idle links become available. 95

When relay 305 operated it connected the office code relays at position 1 with the seized idle marker and closed at its operated contacts an operating circuit for certain relays in the marker translator circuit shown in Fig. 4, the relays operated depending upon the office code relays at the operator's position that were energized by their respectively associated keys. In the case taken for illustration, the operated condition of relays 119, 129 and 137 caused the operations of relays 411 and 412, 407 and 408, 100 and 402 and 404, respectively. 105

The operation of these relays in the marker translator circuit determines the class of trunks necessary for the proper completion of the call and selects the desired group in that class. When relay 410 110 operates an operating circuit for relay 832 of the office register circuit shown in Fig. 8 is closed, the circuit being traceable from battery through the winding of relay 832, contact of relay 803, conductor 816, outer front contact of relay 410, conductor 504, left back contact of relay 508 to ground at the outer right armature of relay 503. Relay 832 operates, therefore, in response 115 to the operation of the key for the first digit of the office designation. In like manner relays 412, 407, 408, 402 and 404 cause the operation of the respective relays 833, 822, 823, 811 and 813 in the sender. These 120 relays all lock to conductor 1104. 125

The operations of the marker registers establish other circuits which operate the trunk group connecting relays and these latter relays provide the means for cross connecting the various combinations set up by the office code keys to determine the class of the trunks desired and to select a particular trunk group of that class. The operations of relays 411 and 412 cause the energization of relay 420 in a circuit extending from battery, through the winding of relay 420, front contacts of relays 411 and 412, to grounded conductor 504. Relay 420 operates and closes the contacts thereof to effect in conjunction with the operated relays 402 and 404 the operation of one of the relays 431, 432 etc., this circuit being traceable from grounded conductor 504, front contact of relay 404, middle back contact of relays 403 and 401, front contact of relay 402, conductor 440, contact of relay 420, cross connected at rack 450, conductor 441 (assuming that this conductor is the one selected in accordance with the office code designation), through the winding of relay 431, to battery, and relay 431 operates. When relays 407 and 408 operated, the following circuit was closed to operate relay 423: grounded conductor 504, front contact of relay 408, front contact of relay 407, through the winding of relay 423, to battery. Relay 423 operates and in conjunction with the contacts operated by relay 431, a conductor, such as 807 for example, is grounded over the operated contacts of relay 423 and a conductor or pair of conductors, such as 433, 434, 435, etc., is grounded over the lower contact of relay 423 and conductor 501. The grounding of a conductor such as 807 operates a relay which controls a trunk group, and the grounding of the conductor or conductors such as 433, 434, 435, etc., determines the class of calls to which the trunk group belongs and operates a relay or a pair of relays depending upon the class of the call, to effect a connection of the impulsing circuit, shown in Fig. 11, with an idle trunk in the selected group.

In the key sets shown in Fig. 1, only eight keys in each row are ordinarily employed for the establishment of the various office codes, the two lower keys designated 0 and 1 not being used. For this reason it will be noted in the marker translator circuit that there are eight relays in the groups numbering 413 to 420, inclusive, which are actuated individually by the various combinations of operated relays 409 to 412, inclusive. On each of the relays 413 and 420 there are also eight contacts which serve to close circuits which were prepared at relays 401 to 404, inclusive, to operate either of the relays 431 and 432. Of the relays 422, 423 and 424, etc., there are eight

likewise, although only three are shown, and each of these is energized by its respective combination established at the relays 405 to 408, inclusive. By means of cross connections on the rack 450, 442 and 443, 70 any of the classes provided and any of the trunk groups in the various classes can be selected by the operator.

The classes of calls provided for in this system, as hereinbefore enumerated, may be 75 established as follows:

1. To a panel type office the conductor 433 will be grounded at the contacts of one of the relays 413 to 420 to operate relay 1101 in a circuit traceable from ground at the 80 outer right armature of relay 502, conductor 501, lower contact of relay 423 (assuming this to be the one in operated condition), operated contact of relay 431, cross connected at rack 443, conductor 433, uppermost front contact of relay 803, conductor 713, through the winding of relay 1101, to battery and relay 1101 operates.

2. To manual offices that are equipped with call indicator equipment and to mechanical offices that are equipped with incoming senders reached by direct trunks there is no class indication, such as, the operation of relay 1101 for the preceding type of call, and trunk groups for this class are seized in the 90 regular way. The numerical designation for the called subscriber's line is established in the numerical registers of the sender, which in conjunction with the impulsing circuit shown in Fig. 11, which is connected to the seized idle trunk by means of the normal contact of relay 1101, controls the necessary 95 impulses to operate the call indicator equipment at the desired office.

3. To a tandem office where the complete 105 subscriber's number is recorded in a tandem sender, two of the conductors such as 434 and 435 will be grounded to operate the relays 1102 and 1103, respectively. The operating circuits are traceable from grounded 110 conductor 501, lower contact of relay 423, operated pair of contacts of relay 431 connected to the conductor associated with the lower contact of relay 423, over parallel conductors 433 and 434, the inner upper front contact of relay 803 and upper front contact of relay 802, conductors 714 and 715, through the winding of relay 1102 to battery and the winding of relay 1103 to battery, respectively, and relays 1102 and 1103 operate.

4. To a tandem office where the office code only is recorded in the tandem sender and the numerical designation is recorded in and transmitted by the sender in the original office for which case, one conductor such as 434, is grounded to close an operating circuit for relay 1102. The operating circuit is traceable as hereinbefore described for relay 1102 and the relay operates.

When the operating circuit for magnet 130

239 was established causing the operation of position finder switch 200 and the subsequent operation of relay 708 a circuit was closed, as hereinbefore stated, through the 5 winding of relay 153 to battery, but relay 153 which is marginal, remained normal in this circuit until relay 708 is energized through its low resistance right hand winding. The operation of relay 708 established 10 an operating circuit for relay 149, the circuit being traceable from ground at the inner left armature of relay 708, conductor 709, operated contacts of sets 254 and 223, conductor 245, through the right hand winding 15 of relay 149 to battery. Relay 149 operates and through its left hand winding locks at its left front contact in a circuit extending to ground at the middle armature of relay 145. Also at the left front contact of relay 20 149, the operating circuit for the sender lamp 147 is opened and the lamp extinguishes, indicating to the operator that an idle sender is seized. At the outer left back contact of relay 149 the locking circuit for relay 201 and the operating circuit for relay 203 are opened and relays 201 and 203 release. At the outer right contact of relay 149 the operating circuit for relay 151 is 25 opened and relay 151 deenergizes. At the make-before-break contact of relay 149, the operating circuit for relays 119 and 141, 129 and 142, and 137 and 143 are opened, but a holding circuit is substituted at the right front contact of relay 149, which extends 30 over conductor 245, operated contacts of sets 223 and 254 to the grounded conductor 709. When relay 149 locks it closes an operating circuit for relay 154 which operates and connects the operator's numerical key set with the seized sender. Should the operator depress the numerical keys before an idler sender is seized, relay 148 will operate and connect the sender lamp 147 with an interrupting ground (not shown) in order to 35 cause a flashing of the lamp which will inform the operator that an idle sender has not as yet been seized. The circuit for effecting the connection of a sender lamp with the interrupting ground may be traced from ground at the depressed key, back contact of relay 154, through the winding of relay 148 to battery.

The release of relays 201 and 203 causes 40 the deenergization of primary vertical magnets 204 and 207 and the relays 209, 213, and 301. The release of magnet 207 opens the original operating circuit for relays 801, 802, 803, 804, but these relays do not deenergize inasmuch as the locking circuit is still closed. The release of relay 301 opens the original operating circuit for relay 503, but the latter relay is maintained operated in its locking circuit. The release of relay 151 opens the original operating circuit for relay 305 but relay 305 is maintained in an operated con-

dition by its locking circuit which extends over conductors 306 and 501 to ground at the outer right armature of relay 502. The release of relay 151 also opens the locking circuit for relay 234 and the operating circuit for relay 236 and the two latter relays deenergize. 70

At the time that relay 305 operated, a circuit was closed at the outer front contact to operate the relay 701 of the non-interfering group which is so arranged that a second marker is prevented from appropriating the trunk and frame connectors during the time that a trunk is being sought. The circuit may be traced from grounded conductor 801, conductor 306, outer front contact of relay 305, conductor 307, through the left hand winding of relay 701 to battery at the inner left armature of relay 702. Relay 701 operates and locks through its right hand winding and the winding of relay 702 to battery. Relay 702 which is common to the non-interfering group operates and opens the original operating circuit for relay 701. When relay 701 operates it closes an obvious operating circuit for relay 703 which is individual to the marker shown. 85

While the classification of the call is being established the desired group is selected by grounding a conductor such as 807 to operate 90 a trunk group relay in the class selected. Assuming that relay 805 controls the desired group, the relay is operated in a circuit traceable from grounded conductor 501, upper contact of relay 423, operated contact of relay 431, conductor 807, cross connected at rack 808, through the winding of relay 805, conductor 704, outer left contact of relay 701 to battery at the outer left armature of relay 702. Relay 805 operates and locks 95 in a circuit extending over conductors 505 and 809 to ground at the inner left contact of relay 503. At the inner and middle right contacts of relay 805, obvious operating circuits are closed for relays 705 and 706 respectively, and at the outer right contact an operating circuit is closed for relay 707, this circuit being traceable from ground, outer right contact of relay 805, cross connected at rack 808, next to the uppermost contact of relay 805, conductor 819, through the winding of relay 707 to battery. Relays 705 and 706 operate to connect the trunk indicating equipment at the operator's position with the seized idle trunk and relay 707 operates to connect the seized idle trunk with the marker and to close operating circuits for the vertical magnets 1001 and 1002 of the trunk selector switch 1000. The operating circuits for the magnets may be traced from a common ground at the outer right armature of relay 502, conductor 537, operated contacts of relays 703 and 707, conductor 717, operated contacts of relays 705 and 706, conductor 718, thence divided over paths individual to 100 105 110 115 120 125 130

the relays 1001 and 1002, the former extending through the outer left contact of relay 805, cross connected at rack 808, conductor 817, operated contacts of relays 703 and 707, 5 conductor 718, through the winding of magnet 1002 to battery and the latter extending through the middle left contact of relay 805, conductors 818 and 716, through the winding of magnet 1001 to battery. Magnets 1001 and 1002 operate and prepare the associated vertical sets of contacts on the selector switch 1000 for connection with their adjacent links. At the contact of magnet 1002, an operating circuit for relay 508 is closed, the circuit 15 being traceable from ground at the contact, conductor 1003, operated contacts of relays 707 and 703, conductor 509, over make-before-break contact and through the winding of relay 508, to battery. Relay 508 operates 20 and opens its own operating circuit at the make-before-break contact, but the relay is held operated in a locking circuit which is substituted at its right front contact, the latter circuit being traceable from battery 25 through the winding and right front contact of relay 508, conductor 505 to ground at the inner left contact of relay 503. The operation of relay 508 establishes an operating circuit for relays 510 and 516 of the trunk test 30 group and this circuit extends from ground at the inner left contact of relay 503, conductor 505, right front contact of relay 508, inner left normal contact of relay 502, inner left contact of relay 508, conductor 539, left 35 back contact of relay 511, (assuming trunk No. 1 of the selected group to be idle this relay will consequently be in a normal condition), through the winding of relay 510, conductor 517, through the winding of relay 40 516, to battery and relays 510 and 516 operate. The operation of relay 508 opens the operating circuits for relays 420, 423, 431, 1101, 1102 and 1103 but only the first three relays release inasmuch as the last three are 45 held if operated over their respective locking circuits. The operation of relay 516 closes an operating circuit for relay 712, the circuit being traceable from ground at the right contact of relay 516, conductor 519, next to the lowermost contact of relay 804, conductor 50 711, through the winding of relay 712, to battery. Relay 712 operates and closes at the next to its innermost armature an operating circuit extending over the right contact of relay 719, through the right hand winding of relay 708, conductor 710, operated contacts of sets 254 and 223, conductor 244, inner left back contact of relay 148, left 55 contact of relay 144, through the winding of marginal relay 153. Relay 153 energizes since the operating circuit therefor, as hereinbefore explained, extends through the right hand low resistance winding of relay 708. Also at relay 516 an operating circuit is 60 closed at the left contact to operate the relay 602 and this circuit may be traced from ground at the left armature of relay 516, conductor 520, lowermost contact of relay 305, conductor 321, right contact of relay 153, conductor 155, through the winding of relay 602, to battery. Relay 602 operates and locks, and opens the operating circuit for no-trunk lamp 601. The lamp extinguishes indicating to the operator that an idle trunk is seized. At the inner right front contact 65 of relay 510, an operating circuit is closed for the horizontal magnet 1004 (assuming that the associated link 1008 is idle inasmuch as it is assumed that its corresponding relay 511 is in a non-operated condition), the circuit being traceable from ground at the inner right armature of relay 510, conductor 518, operated contacts of relay 703 and 707, conductor 1007, through the right hand winding of magnet 1004 to battery. Magnet 1004 operates and connects the vertical contact sets 1022 and 1023 which were 70 prepared for connection with an idle link by the operation of their respective vertical magnets 1001 and 1002, and the first idle 75 trunk of the desired group of the trunk selector switch 1000 is seized. When magnet 1004 operates it closes a holding circuit for itself at the operated contacts of set 1022, the circuit being traceable from battery, 80 the two windings in series of magnet 1004, lowermost contact of set 1022, conductor 711, next to the lowermost contact of relay 804, conductor 519, to ground at the outer right 85 armature of relay 516. 90

The trunk translator relays shown in the central part of Fig. 5 are arranged in groups representing the units and tens of the trunk jack numbering of the switchboard multiple. Each units group contains five relays, such 95 as relays 521 to 525, four of which have two windings and the other has one, and each winding is shown numbered to correspond with its associated trunk in the multiple and is arranged to be energized when its associated trunk on the selector frame vertical is seized. The tens relays consist of relays 526, 532, etc., one for each units group except the first. These tens relays are energized 100 when their respectively associated trunks are seized. These relays are operated in conjunction with the testing relays, such as when test relay 510 which is associated with trunk 1011 at the selector switch is operated. The trunk jack 1016 which is connected with the seized idle trunk 1011 bears no fixed relation with respect to its position in the multiple to the position of the trunk at the selector switch frame vertical. In cases where the trunk groups are small it is necessary 105 to form multiples and the circuit must be so arranged that the same indication will be 110 given the operator of the seizure of any trunk 115 120 125

in a multipled group no matter what position it might have on the selector frame. Therefore, to provide a satisfactory trunk indicating scheme, the set of translating relays is furnished to translate the position number of the seized trunk at the selector frame vertical into the number of its associated jack appearing in front of the operator. Upon the seizure of an idle trunk 10 certain relays associated therewith in the translator group are operated and establish a circuit for operating a relay or a combination of relays to cause the number of the trunk jack connected to the seized trunk to be displayed at the operator's position. The scheme of trunk indicating is accomplished through the operation of test relay 510 which is, when engaged in testing the selected group, individual to the seized trunk 1011, the position of which is number 1 on the frame vertical. Relay 510 closes at its right contact an operating circuit for relay 522 of the translating group, the circuit being traceable from ground at the inner left contact of relay 503, conductor 505, outer right contact of relay 510, conductor 534, operated contacts of relays 706 and 705, multipled at relay 705 to the lowermost contacts thereof, conductor 533, through the left hand winding of relay 522 to battery. Relay 522 operates and closes at its outer contact a circuit to operate relay 606, the circuit being traceable from ground at the outer contact of relay 522, conductor 536, operated contact of relay 305, conductor 359, through the winding of relay 606, to battery. Relay 606 operates and locks in a circuit extending over conductors 643 and 642, left contact of relay 153, to ground at the inner left armature of relay 145. The operation of relay 606 closes an operating circuit for lamp 621 in the units group of the trunk indicator and the lamp being the No. 1 of the group, lights indicating to the operator that the trunk connected to the multiple jack No. 1 is seized. The indicator lamps designated 620 to 629 represent the units, 0 to 9, respectively, and those designated 630 to 639 represent the tens, 0 to 9. Should the trunk seized correspond to trunk jack No. 6, the right hand winding of relay 522 would be energized and would cause the operation of relays 604, 605 and 606 to light the lamp 626, which is number 6 in the unit group of lamps and corresponds to trunk jack No. 6. Should the trunk seized at the frame vertical be connected to trunk jack No. 11, relays 528 of the first group of tens in the trunk translating relays would be energized over its left hand winding in series with the winding of relay 526 and relays 531 and 526 would operate, thereby causing the operation of relay 611 in the tens group of the indicator and relay 606 in the units group to light the lamp 631 in the tens group and lamp 621

in the units group, these lamps corresponding to jack number 11 in the multiple.

When magnet 1004 operated it completed the connection of link 1008 with the contact sets 1022 and 1029 thereby seizing idle trunk 1011 and connecting it to the seized sender. The connection of link 1008 with contact sets 1022 and 1029 closes an operating circuit for marker release relay 502, the circuit being traceable from battery, through the winding of relay 502, conductor 544, left front contact of relay 510, conductor 545, operated contacts of relays 706 and 705, conductor 1024, normal contact of relay 1025, conductor 1028, operated contact sets 1029 and 1022, conductor 711, right front contact of relay 708, to ground at the middle armature of relay 712. Relay 502 operates and closes a locking circuit for itself to ground at the left contact of relay 503 and also opens the circuits of relays 305, 503, 510 and 516 and magnets 1001 and 1002. The release of relay 503 opens the locking circuit for relays 801, 802, 803, 804 and 805 and these relays also release. Relay 503 on releasing also opens the locking circuit of release relay 502. The release of relay 305 effects the deenergization of relays 701 and 702 which subsequently open the operating circuit for relay 703. The release of relay 805 causes the release of relays 705, 706 and 707. The release of relay 510 causes the deenergization of relay 522 and the release of relay 305 disconnects the marker from the operator's position thereby deenergizing relays 402, 404, 407, 408, 411 and 412 so that now marker No. 1 is available for another call.

Should it be desired to complete a second call through the same group of trunks while the first trunk, which in this case is designated 1011, is busy, the operation of relays 706 and 705 for the second time, would complete an operating circuit for relay 511, the circuit extending through the right hand winding of relay 511, inner left back contact of relay 510, conductor 545, operated contacts of relays 706 and 705, conductor 1024, to ground at the left contact of sleeve relay 1020 and relay 511 would operate and prepare at its left contact an operating circuit for the relay 512 to test trunk 1012 for a busy condition. Should trunk 1012 be also busy relay 513 would likewise be found in an operated condition and the trunk test operating circuit would be closed at the left contact of relay 513 to operate the next test relay and should the next trunk be busy the operating circuit would be extended until an idle trunk in the desired group is found.

While the above operations are in progress the sender has been awaiting the seizure of an idle trunk which in this case is assumed to be 1011. The impulsing circuit shown in Fig. 11 is connected with trunk 130

1011 by means of conductors 1109 and 1110 over the operated contact sets 1022 and 1029 of the trunk selector switch 1000.

When the operator depresses the office code 5 keys lamp 147 lights indicating, as hereinbefore stated, that an idle sender is being sought, but as soon as the light extinguishes which indicates that a sender is connected to the position the operator depresses the keys 10 in row D for the numerical designation of the called subscriber's number. The numerical designation as hereinbefore stated is 1 2 3 6 and the operator accordingly starts by depressing key 1 in row D. The operation 15 of key 1 closes an operating circuit for relay 910 of the thousands registers and the circuit is traceable from ground at the operated key 1, conductor 158, uppermost front contact of relay 154, conductor 159, operated 20 contacts of sets 223 and 254, conductor 267, left back contact of relay 914, through the winding of relay 910 to battery. Relay 910 operates and locks in a circuit extending through the windings of relays 915 and 914 25 in series, conductors 903, 904 and 1104 to ground at the outermost armature of relay 712. Relay 910 in operating stores the first digit of the numerical designation. When key 1 releases it opens the original operating 30 circuit for relay 910 and permits relays 915 and 914 to operate so as to close a circuit for the second digit to operate the necessary relay or relays in the hundreds registers. The operating circuit for register relay 910 35 shunts the register relays of the second digit and therefore prevents the false operation of the register relays of the second digit until key 1 is released. The operator depresses key 2 for the second digit and the 40 operation of this key closes an operating circuit for relay 921, the circuit being traceable from grounded key 2, conductor 160, next to the uppermost front contact of relay 154, conductor 161, operated contacts of sets 223, 45 conductor 254, right front contact of relay 914, right back contact of relay 924, through the winding of relay 921, to battery. Relay 921 operates and locks in a circuit extending through the windings of cut-in relays 925 50 and 924 in series, over the conductors 904 and 1104 to ground but as described for the first digit relays 925 and 924 do not operate until key 2 is released. Relay 921 now stores the second digit of the numerical 55 designation. In like manner the operator depresses key 3 for the third digit, but in this case two circuits are closed to operate two relays in the tens, or third set, of registers, the relays operated being 930 and 931 which 60 lock in parallel in a circuit extending through the windings of cut-in relays 935 and 934 in series to grounded conductor 1104 and relays 935 and 945 operate the operation of the cut-in relays depending, as in the 65 preceding cases, on the release of key 3.

The fourth, or final digit, of the numerical designation is recorded by depressing key 6 and in this case also two circuits are closed to operate two relays in the units, or fourth set, of registers, the relays operated being 70 940 and 943. These relays lock in parallel in a circuit extending through the windings of cut-in relays 945 and 944 in series to grounded conductor 1104 and relays 945 and 944 operate when key 6 is released. The 75 numerical designation is now stored in the numerical registers of the sender. In order to explain the operation of the various circuits required for the different classes of calls, it will be necessary to explain the functions of each class separately. 80

Call direct to panel type office.

The first class of call to be considered will be to a panel type office and the relay 1101, 85 the operation of which was hereinbefore described will be regarded as being in an operated condition. The operation of relay 1101 closes a locking circuit for itself extending from battery through the winding 90 and left contact of relay 1101, conductor 1104, to ground at the outermost left armature of relay 712. At the inner right contact of relay 1101 an operating circuit is closed for relay 1105, the circuit being traceable from battery through the winding of relay 1105, inner right contact of relay 1101 to ground at the next to the outermost armature of relay 712. Relay 1105 operates and connects by means of the conductors 1109 95 and 1110 the impulsing circuit with trunk 1011 which is now in a position to receive the numerical designations of the called subscriber's line. 100

The operation of relay 910 of the numerical registers closes an operating circuit for relay 1301 of the panel register circuit for the selection of the incoming brush at the distant office, the circuit being traceable from grounded conductor 903, inner left contact 105 of relay 910, conductor 926 through the winding of relay 1301 to battery, and relay 1301 operates. In like manner, the operation of relays 921 representing the hundreds digit, relays 930 and 931 representing the tens digit and 940 and 943 representing the units digit of the called subscriber's number close at their respective inner left contacts operating circuits for their respectively associated relays 1306 for the incoming group and final brush selection, 1309 and 1310 for the tens selection, and 1313 and 1316 for the units selection and relays 1303, 1309, 1310, 1313 and 1316 operate. The operation 110 of these relays in the panel register circuit effects, in conjunction with the counting relays, shown in the upper part of Fig. 12, the translation of the numerical designation into impulses required for the selection of the final frame choice at the incoming frame 115 120 125 130

and the line at the final frame at which the elected choice terminates.

The operation of relay 915 closed an operating circuit for relay 1201, the circuit being traceable from ground at the inner lower contact of relay 1105, conductor 1111, left contact of relay 1202, conductor 1203, outer right front contact of relay 915, conductor 905, outer right contact of relay 1204, through winding of relay 1201, to battery. Relay 1201 operates and closes a holding circuit for itself over its inner left contact, make-before-break contact, and right hand winding of relay 1204, conductors 1212, to grounded conductor 904. Relay 1204 being shunted by the direct ground in the operating circuit for relay 1201 does not operate at this time. Relay 1201 also closes an operating circuit for relay 1205 and the circuit may be traced from battery, through the winding of relay 1205, middle right contact of relay 1201, conductor 1206, to ground at the right armature of relay 1202. Relay 1205 operates and closes at its left contact an operating circuit, generally known as the fundamental circuit, for the stepping relay 1207, which circuit is traceable from ground and battery at the distant office, over the tip and ring conductors of the seized trunk, conductors 1109 and 1110, and over the operated uppermost and lowermost contacts of relays 1105, the tip side extending over conductor 1112, through the winding of relay 1207, left contact of relay 1205, contact of counting relay BO', conductor 1209, through the right hand winding of polarized relay 720, conductor 721 to the lowermost operated contact of relay 1105. Relay 720 being polarized and arranged to operate in a circuit of opposite polarity to that of the circuit just traced, does not operate. The source of battery supply for operating the stepping relay is connected with the winding of the incoming line relay at the distant office and the line relay being arranged in series with the stepping relay is also energized when relay 1205 closes the circuit. The operations performed at the distant office (not shown but generally known) are as follows: the line relay locks and closes an operating circuit for the rotary magnet of an incoming sequence switch and the rotary magnet operates and moves the sequence switch into position 2, the incoming brush selection position. The operation of the line relay also closes an operating circuit for the up-drive clutch magnet of the incoming switch which magnet energizes and starts the upward motion of the selector brush rod carrying the commutator brush across the segments of the commutator. When the commutator brush strikes the first metal segment, the line relay will have two paths, one extending to ground at the commutator brush and the other extending to ground

through the winding of the stepping relay. The latter path being shunted will cause the stepping relay to deenergize. While the stepping relay is shunted the line relay will be held operated and the selector brush rod will continue to move upwards until the commutator brush comes in contact with an insulative segment at which point the shunt around the stepping relay is removed and the stepping relay energizes. Each time that the commutator brush comes in contact with an insulative segment a counting relay in the originating office is energized and the point at which the commutator brush stops is controlled by counting relay 0, and the operation of this relay causes the operation of counting relay BO' which operates and opens the fundamental circuit permanently. The operation of the BO' counting relay causes the stepping relay and the line relay to deenergize and the deenergization of the latter relay opens the operating circuit for the up-drive magnet and the upward motion of the selector brush rod is stopped. The deenergization of the line relay also causes the rotary magnet to operate and move the sequence switch into position 3. Each time that the line relay is energized and deenergized, the sequence switch is moved to a new position, the even position up to and including a certain position being those of selections, such as incoming group, trunk hunting, final brush, tens, and units and the odd positions being those of "waiting". As the brush rod on the incoming frame in the distant office moves upwardly the commutator brush moves over the first metal segment of the commutator and a holding circuit is closed for the incoming line relay, and the fundamental circuit is opened, the opening of the latter circuit causing relay 1207 to deenergize. The deenergization of relay 1207 opens the operating circuit for counting relay number 0 and removes the shunt which heretofore prevented counting relays FO' and BO' from operating and relays FO' and BO' operate. As just stated the operation of counting relay BO' maintains the fundamental circuit open but the line relay is held operated in a circuit extending over the contact between the commutator brush and the first metal segment, and the upward movement of the selector brush rod continues until commutator brush passes over the metal segment on to an insulative segment at which point the line relay deenergizes and the movement of the selector brush rod stops. Therefore, in response to the operation of key No. 1 for the called subscriber's number, a circuit is closed to operate counting relay No. 0, the circuit being traceable from ground at relay 1207, conductor 1210, inner right contact of relay 1201, conductor 1211, left back contact 130

of relay 1304, outer left back contact of relay 1302, left contact of relay 1301, conductor 1216, outer left contact of relay 1201, conductor 1214, through the winding of counting relay No. 0, to battery and counting relay No. 0 operates. The operation of counting relay No. 0 closes parallel operating circuits for counting relays BO' and FO'. Counting relay BO' operates and opens the fundamental circuit permanently and the line relay deenergizes thereby causing the incoming brush rod to stop after it has moved upwardly one step in response to the one impulse and incoming brush associated with the first bank at the incoming selector frame is tripped for further operation. The operation of counting relay FO' closes an operating circuit for relay 1202 which operates and opens at its right contact the operating circuit for relay 1205. Relay 1205 deenergizes and opens at its left contact another point in the fundamental circuit. When relay 1202 operates it opens the original operating circuit for relay 1201 but the holding circuit, described above, maintains relay 1201 in an operated condition and the relay 1204 which was shunted by the original operating circuit for relay 1201, is now permitted to operate. Relay 1204 operates and locks over its left hand winding and opens at its make-before-break contact the holding circuit for relay 1201. Relay 1201 deenergizes causing thereby the release of the counting relays and relay 1202 and the closure of the fundamental circuit at the contact of the BO' counting relay. The counting relays are now ready for the second set of operations, or the incoming group selection.

When relay 1204 operates it closes an operating circuit for relay 1220 extending from grounded conductor 1111 left contact of relay 1202, conductor 1203, outer right front contact of relay 925, conductor 1219, right back contact of relay 1223, right back contact of relay 1221, right front contact of relay 1204, through the winding of relay 1220, to battery. Relay 1220 operates and establishes an operating circuit similar to that established by the operation of relay 1201, for relay 1205, and relay 1205 operates thereby closing for the second time the fundamental circuit which causes relay 1207 to operate. The operation of relay 1220 closes an operating circuit for counting relay No. 7 extending from ground at the armature of relay 1207, conductor 1210, inner right contact of relay 1220, conductor 1320, front contact of relay 1317 (this relay being operated in the circuit which was closed at the outer right front contact of relay 1301), left back contact of relay 1318, right back contact of relay 1308, conductors 1323 and 1320, through the winding of

counting relay No. 7 to battery. Counting relay No. 7 operates and locks in a circuit extending through the winding of counting relay No. 7', conductor 1213, outer right contact of relay 1220, conductors 1212, to 70 grounded conductor 904, but counting relay No. 7' is shunted by the direct ground in the operating circuit for counting relay No. 7 and therefore does not operate at this time. When the fundamental circuit was 75 closed, the selector brush rod on the incoming frame moved upwardly causing the commutator brush to pass over the metal and the insulative segments of the commutator and therefore the circuit for stepping relay 1207 was intermittently shunted. Each time that the commutator brush comes in contact with a metal segment on the commutator, relay 1207 is short circuited and released causing thereby the operation of 80 a pair of counting relays, and the movement of the commutator brush is continued until the pair of counting relays, No. 0 and FO', is operated. Simultaneous with the operation of relay FO' is the operation of relay 90 BO' and the operation of the latter relay effects a permanent opening of the fundamental circuit which causes the commutator brush to stop on the desired contact. This 95 intermittent action of the relay 1207 results in the successive actuation of the counting relays Nos. 6' and FO' so that when three impulses have been received, corresponding to the elevation of the selector brush to the third group of trunks of the first bank, selector brush to the third group of trunks of the first bank, the fundamental circuit is opened, causing the advance of the incoming sequence switch. The upward movement of the brush rod is then continued 100 to 105 in the well known manner until an idle trunk in the selected group is seized. The counting relays and relays 1205, 1202 and 1207 deenergize, as was described above.

When the operating circuit for the relay 110 1220 is opened the holding circuit extending through the winding of relay 1221 causes the operation of the latter relay which operates and opens at its make-before-break contact the holding circuit for relay 1220 and 115 relay 1220 deenergizes. The counting relays are now positioned to be energized for the transmission of the third set of impulses. When relay 1221 operates it closes at its left contact a locking circuit extending 120 through its left hand winding to battery, also at the right front contact an operating circuit for relay 1222 is closed and the circuit is similar to that traced above for relay 1220 except that the right front contact instead of the right back contact of relay 1221 is closed, thereby extending the circuit through the winding of relay 1222, to battery. Relay 1222 operates and at its inner 125 left contact locks in a circuit extending 130

through the right hand winding of relay 1223, but like relays 1204 and 1221, as described above, relay 1223 is shunted and does not operate at this time. At the middle 5 right contact of relay 1222 a circuit is closed to again operate relay 1205, the operation of which closes the fundamental circuit for operating the line relay in the distant office and stepping relay 1207. At the inner right 10 contact of relay 1222 a circuit is closed to operate counting relay No. 7, the circuit being traceable from battery through the winding of counting relay No. 7, back contact of counting relay No. 7', conductors 15 1320 and 1323, right contact of relay 1305, outer left front contact of relay 1306, right back contact of relay 1307, conductor 1218, inner right contact of relay 1227, conductor 1210, to ground at the armature of relay 20 1207. Since the first impulse causes counting relay 7 to operate, counting relays BO' and FO' will be operated when three impulses have been received. Similar to the incoming group and trunk hunting selections, when the counting relay BO' is operated, stepping relay 1207 deenergizes and the operating circuit for relay 1222 is opened causing the energization of relay 1223. Also when counting relay FO' operates, relay 30 1202 consequently operates to effect the release of relay 1205, and relay 1202 is restored when counting relay FO' is deenergized.

When relay 1223 operates it prepares a 35 counting relay for the transmission of the fourth set of impulses, or that set which corresponds to the tens digit of the called subscriber's number, by closing a circuit extending from grounded conductor 1203, outer right front contact of relay 935, conductor 906, right back contact of relay 1225, right front contact of relay 1223, through the winding of relay 1224, to battery. Relay 1224 operates and locks through the 40 right hand winding of relay 1225 without affecting the latter relay. Relay 1205 is again operated to close the fundamental circuit and to cause ground potential to be connected at the armature of stepping relay 45 1207. At the inner right armature of relay 1224 an operating circuit is closed for counting relay No. 8 and the circuit may be traced from grounded conductor 1210, inner right contact of relay 1224, conductor 1219, right 50 back contact of relay 1311, outer left front contact of relay 1310, right front contact of relay 1309, conductor 1321, right back contact of counting relay No. 8' through the winding of counting relay No. 8 to battery. 55 Counting relays Nos. 8, 7, 6 and 0 are operated in succession by the four impulses transmitted by the movement of the final switch in selecting the fourth group of ten lines to which the third brush of the final 60 selector has access.

In a manner similar to the above cases described relay 1224 is deenergized and relay 1225 operates thereby closing an operating circuit for relay 1226 which prepares the counting relays for the transmission of the fifth set of impulses, or that set which corresponds to the units digit of the subscriber's number, the circuit being traceable from grounded conductor 1203, right 70 front contact of relay 945, conductor 907, right 75 contact of relay 1227, right front contact of relay 1225, through the winding of relay 1226, to battery. Relay 1226 operates and locks, and relay 1205 and 1207 are subsequently operated. The operation of relay 80 1207 closes an operating circuit for counting relay No. 6 and the circuit may be traced for the grounded conductor 1210, inner right contact of relay 1226, conductor 1228, right back contact of relay 1315, outer left back 85 contact of relay 1314, inner left front contact of relay 1313, conductor 1317 right back contact of counting relay No. 6' through the winding of counting relay No. 6, to battery. Counting relay No. 6 is operated by the first impulse, and inasmuch as relay 1316 is in an operated condition, counting relays 5, 4, 3, 2, 1 and 0 are operated in succession by the remaining impulses transmitted by the final switch in selecting the 90 seventh line of the tens group previously selected. The subscriber's line corresponding to the number 1236 is now connected to the trunk 1011 and ringing current is connected at the distant office to the called subscriber's line. Like in the previous case, the energization of counting relays BO' and FO' effect the release of the relays 1205, 1207 and 1226 and subsequently all the 95 counting relays release. However, the relay 1227 is maintained in operated condition until the sender is released.

When the last impulse is transmitted and the desired subscriber's line is connected to the seized trunk the distant sequence switch 100 moves into ringing position and thereby causes a reversal in the direction of the current flow in the fundamental circuit which has again closed after the transmission of the last impulse. This change in current 105 flow effects the operation of polarized relay 720 thereby preparing the sender to release. The release of the sender is effected in conjunction with the insertion of the calling end of the cord 1015 into jack 1016.

Call through call indicator equipment.

If it is desired to complete a call through the call indicator equipment in a manually operated office, or in either of a coordinate or a panel machine switching office in which incoming senders are employed, the class of call will not be indicated by the operation of any controlling relays in the impulsive circuit shown in Fig. 11, and as 125 130

was previously described in the call direct to the panel type office in which case relay 1101 was operated. In the call indicator class of call the relay 1101 remains normal and the operation of relay 712, as hereinbefore described, closes an obvious operating circuit for the starting relay 1106. Relay 1106 operates and locks at its inner lower front contact in a circuit extending to ground over the conductor 1104. The operation of relay 1106 causes tip and ring conductors 1109 and 1110, associated with the seized idle trunk which is assumed in this case to be 1011, to be connected to the impulsive circuit, and relay 1108 is operated in the well known manner in a circuit extending over the tip and ring conductors of the trunk to a line relay which is bridged across the trunk circuit at the distant office. The line relay operates and causes the subsequent operation of a connecting relay which connects a call indicator control circuit at the distant office to the seized idle trunk. The operation of the connecting relay disconnects the line relay from the trunk and the trunk circuit is then closed through a dry bridge comprising a chain of two polarized relays and one marginal relay in place of the line relay or wet bridge. When relay 1108 operates, it closes at its contact an obvious operating circuit for relay 1113 and relay 1113 operates and closes a holding circuit for itself, the holding circuit being traceable from battery, through the winding of relay 1113, through the winding of start relay 1107, left contact of relay 1113, back contact of relay 1116, to grounded conductor 1104. Relay 1107 operates and disconnects relay 1108 from the trunk and the latter relay releases thereby opening the original operating circuit for relay 1113.

The operation of relay 1113 closes a circuit extending from battery, through the winding of relay 1114, conductor 1117, outer left contact of relay 815, conductor 916, outer left contact of relay 951, outer left front contact of relay 914, conductor 908, right contact of relay 1113, left back contact of relay 1116, to grounded conductor 1104, and relay 1114 operates and closes an operating circuit for relay 1115, the circuit being traceable from ground at the middle left armature of relay 1114, normal contact of relay 1118, normal contact of relay 1119, through the winding of relay 1115, to battery at the middle left armature of relay 1120. Relay 1115 operates and connects ground to both the tip and the ring side of the trunk and thereby holds the line relay operated until the connecting relay is energized to connect the seized trunk with the call indicator control circuit. The operation of relay 1115 closes an operating circuit for relay 1119, the circuit being traceable from battery, through the winding of relay

1119, inner lower front contact of relay 1115, normal contact of relay 1118, middle armature of relay 1114 to ground. Relay 1119 operates and closes at its outer right contact an obvious locking circuit for relay 1114 and an operating circuit for cut-in relay 950 of the thousands registers of the sender, the latter circuit extending from battery, through the winding of relay 950, inner right back contact of relay 951, conductor 919, left back contact of relay 1102, contact of relay 1129, conductor 1128, to ground at the outer right armature of relay 1119. Relay 1119 locks at its left front contact in a circuit which may be traced over its left front contact, normal contact of relay 1118 to ground at the middle left armature of relay 1114. Relay 950 operates and closes a locking circuit for itself over its inner left front contact, conductor 909, through the winding of relay 1129, conductor 1128 to ground at the outer right armature of relay 1119. Relay 1129 does not operate at this time because a shunt exists in the original operating circuit just traced, for relay 950. The operation of relay 1119 causes the release of relay 1115 which effects the closure of the trunk circuit for the first impulse to be transmitted to the call indicator equipment at the distant office. The release of relay 1115 opens the original operating circuit for relay 1119 and closes at the inner lower back contact of relay 1115 an operating circuit for relay 1121, one of a pair of interrupting or timing relays, and the circuit may be traced from battery, through the winding of relay 1121, left back contact of relay 1122, left back contact of relay 1123, inner right contact of relay 1119, inner lower back contact of relay 1115, to ground at the inner lower armature of relay 1107. Relay 1121 operates and closes at its outer left front contact an operating circuit for relay 1122, the other of the interrupting or timing relays, and the circuit may be traced over the left back contact of relay 1121 and thence over practically the same path as that for relay 1121. Relay 1122 operates and opens at its outer left contact the operating circuit for relay 1121 and relay 1121 releases. It is seen that the operation of either of these relays effects the release of the other and the release of relay 1122 permits relay 1121 to reenergize and this action is continued as long as relay 1107 is in operated condition. The purpose of the interrupting relays is to provide a cycle of operations of some of the relays in the impulsive circuit for each digit so as to regulate and control the impulses transmitted to the distant office, as will be explained in detail.

As it is well known, the common practice for establishing a call through call indicator equipment is to send four pulses for

each numerical digit of the called subscriber's number and in order to explain the operation of the circuit which effects the transmission of these impulses, it is believed that an explanation of the means for sending the four impulses for the first digit only will be sufficient to give a good idea of the operation of the impulsing circuit. The relays which regulate and control the transmission of the impulses comprise two sets of advance relays such as 1123 and 1124 and 1126 and 1127 and a set of interrupting or timing relays such as 1121 and 1122 and these relays in conjunction with a reversing relay such as 1125 effect a cycle of relay operations for each digit of the called subscriber's number. As stated before, when relay 1115 releases the first impulse is transmitted over the trunk and this impulse being positive in its direction, is sent over the ring side, the circuit for the impulse being traceable from battery through the high resistance 828, conductor 927, left back contact of relay 912, outer left contact of relay 910, outer back right contact of relay 951, conductor 928, outer right contact of relay 1102, outer right contact of relay 1114, outer right contact of relay 1126, upper normal contact of reversing relay 1125, over the tip side of the trunk, across the dry bridge of the two polarized and one marginal relays at the distant office, over the ring side of the trunk, lower normal contact of relay 1125, inner left front contact of relay 1114, to ground at the inner lower armature of relay 1107. In conjunction with the release of relay 1115, relay 1119 operates and closes the operating circuit for relay 1121 and when relay 1121 operates, it closes an operating circuit for relay 1124, the circuit being traceable from ground at the right contact of relay 1121, inner right back contact of relay 1123, through the winding of relay 1124, through the right hand winding of marginal relay 1123 to battery. Relay 1124 operates but relay 1123 being marginal remains normal in this circuit. Relay 1122 having operated subsequently to the operation of relay 1121, causes the release of the latter relay which now opens at its right contact the operating circuit for relay 1124, but relay 1124 when it previously operated closed at its right contact a shunted circuit traceable from grounded conductor 1104, right contact of relay 1124, through the left hand winding of relay 1123, through the winding of relay 1124, through the right hand winding of relay 1123, to battery and this shunted circuit is now permitted to energize relay 1123. Relay 1123 operates and, when relay 1121 operates again in its regular sequence, locks itself in a circuit extending to ground at the right contact of relay 1121. The closing of the locking circuit places a shunt around the original operating

circuit for relay 1123 and relay 1124 de-energizes but relay 1123 being in an operated condition holds its armature up until relay 1121 releases and opens the holding circuit. When relay 1123 operates it closes an obvious operating circuit for reversing relay 1125 which operates and ends the first impulse by reversing the connections of the tip and ring conductors of the trunk with the conductors of the impulsing circuit. The transmission of the first impulse causes the subsequent operation of a relay of a group of four which is associated with the thousands group of lamps in the call indicator at the distant office and it depends upon the energized and deenergized condition of these four relays as to which lamp in each group will be lighted.

The reversal of the current due to the energization of relay 1125 sends a second impulse over the ring side of the trunk and the circuit for this impulse may be traced from battery, high resistance 828, conductor 927, inner and outer lower front contacts of relay 1125, ring side of trunk, over the dry bridge at the distant office, tip side of the trunk, upper front contact of relay 1125, inner left front contact of relay 1114, to ground at the inner lower armature of relay 1107. At the beginning of the second impulse, relay 1121 is in an operated condition for the second time and effects also for the second time the operation of relay 1122 which, as stated before, effects the subsequent release of relay 1121. The release of relay 1121 opens the locking circuit for relay 1123 and the latter relay releases effecting thereby the subsequent release of relay 1125. When relay 1121 releases, it opens the operating circuit for relay 1122 which releases and immediately upon the release of relay 1122, relay 1121 becomes reenergized. The release of relay 1123 opens the original operating circuit for relay 1126 but the latter relay is maintained in an operated condition over a holding circuit extending through the right hand winding of marginal relay 1127, inner right contact of relay 1126 to grounded conductor 1104 and relay 1127 now operates. The release of relay 1125 ends the second impulse and causes another reversal in the direction of the current over the trunk. In view of the high resistance 828 being in the circuit for the second impulse, the impulsing current is a light negative and operates a second relay in the group associated with the thousands lamps in the call indicator.

The release of relay 1125 prepares the trunk circuit for the third impulse, but inasmuch as relay 1126 is in an operated condition, the fundamental path of the impulsing circuit is opened at the outer left contact of relay 1126 and no current is sent for this period. At the beginning of the

third impulse or period, relay 1121 becomes operated, which starts the operation of relays 1122 and 1124, and relay 1123 having deenergized during the second impulse effects the operation of relay 1127 which is now energized in series with relay 1126. The operation of relay 1124 closes an operating circuit for relay 951, the circuit being traceable from battery, through the winding of relay 951, right contact of relay 950, conductor 918, outer right contact of relay 1126 to ground in the left armature of relay 1124. Relay 951 operates, connects the trunk with the hundredths register of the sender through a conductor which is normally in contact with the tip side of the trunk and prepares an operating circuit for relay 952. When relay 951 operates, it locks in a circuit extending over its inner left contact to conductor 904 which connects with the grounded conductor 1104. The operation of relay 951 opens the original operating circuit for relay 950, and relay 1129, which is in the locking circuit for relay 950, operates in order to prevent at this time, the operation of relay 952 which is associated with the hundredths register. When relay 1122 operates and effects the release of relay 1121, relay 1123 operates and the operating condition of the last mentioned relay together with that of relay 1127 closes an operating circuit for relay 1118, the circuit being traceable from battery, through the winding of relay 1118, inner left contact of relay 1123, outer right contact of relay 1127, normal contact of relay 1118, to ground at the middle armature of relay 114. Relay 1118 operates and locks in a circuit extending over its front contact to ground at relay 1114. The operation of relay 1118 substitutes a new holding circuit for relay 1119, the circuit extending through the outer right contact of relay 1127, inner left contact of relay 1123, off normal contact of relay 1118 to ground at relay 1114. The operation of relay 1123 connects ground to conductor 1131 causing relay 1127 to lock in a circuit which shunts the winding of relay 1126 causing thereby the release of relay 1126 which opens the original operating circuit for relay 951. Likewise, the operation of relay 1123 effects the energization of relay 1125 which operates to terminate the period for the third impulse. Inasmuch as no current is sent during this period, the third relay of the group associated with the thousands lamps remains normal.

When relay 1125 operates for the termination of the period for the third impulse and the beginning of the fourth, relay 1121 becomes operated again as in the other three periods and effects the operation of relay 1122 and the release of relay 1124 as before. The fourth impulse is produced by a light negative current through the same circuit

that was traced before for the second impulse. During the time that the fourth impulse is being transmitted, relays 1121 and 1122 deenergize and the release of relay 1121 again causes the release of relay 1123 which subsequently releases relays 1125 and 1127. The release of relay 1123 opens the substitute holding circuit for relay 1119 and the latter relay releases and connects battery at its outer left armature to the locking circuit for relay 1118, the winding of which is consequently shunted and relay 1118 deenergized. Transmission of the fourth impulse operates a fourth relay of the group associated with the thousandths lamps and this impulse completes the combination of energized and deenergized relays necessary to light the No. 1 lamp which corresponds to the thousandths digit of the called subscriber's number.

The hundredths, tens, and units digits of the called subscriber's number are recorded in their respective lamp groups in the same manner as described for the thousandths digit, and the proper sequence of the respective sets of impulses is controlled by the cut-in-relays such as 950, 952, 954, and 956 in conjunction with relay 1119 which is operated at the beginning of each period and remains in such condition until the end of the period. The nature of the impulses depends upon the operated or non-operated condition of relays 1126 and 1127, at the time that each impulse is being transmitted, together with the relays of the numerical registers in the sender shown in Fig. 9. When relay 1119 is released, it is immediately reenergized by the reenergization of relay 1115, and this arrangement provides the means for completing the sets of four impulses for each digit separately. As the fourth period is completed, the lamps Nos. 1, 2, 3 and 6 for the thousands, hundreds, tens and units digits, respectively, are lighted and indicate to the operator at the distant office that the subscriber's station No. 1236 is wanted and the connection is established in the regular way. For the duration of the four periods, relays 1106, 1113, 1107, 1114 remain operated and are not released until the sender is restored to normal.

When the last impulse is transmitted relay 720 is operated in a circuit hereinafter described and prepares the sender for its release which is effected when the calling end of cord 1015 is inserted in jack 1016.

Call through a tandem office in which the complete number of the subscriber's line is recorded in the tandem sender.

If it is desired to complete a call through a tandem office in which the complete subscriber's number is established in the tandem sender and relayed therefrom to the

terminating office, this class of call will cause the operation of relays 1102 and 1103 of the impulsing circuit as hereinbefore described. In this class of call, relay 1101 remains normal and in conjunction with relay 712, in an operated condition provides an operating circuit for relay 1106. Relay 1106 operates and causes the subsequent operation of relays 1108, 1113, 1107, 1114, 1115 and 1119, and the operation of relays 1107 and 1119 effect the release of relays 1108 and 1115, respectively. The operating circuits for the above enumerated relays are the same as just traced for the call through the call indicator equipment. Inasmuch as relay 1102 is in an operated condition, an obvious operating circuit for relay 834 is closed at the outer left front contact of relay 1102, and relay 834 operates and prepares the necessary circuits for the transmission of the impulses for the first digit of the office code. Relay 834, like the other cut-in relays 950 to 956, described in the call indicator type of call, locks in a circuit extending over conductor 909, through the winding of relay 1129, to ground at the outer right armature of relay 1119, but this locking circuit, like those for the other cut-in relays, is shunted by the original operating circuit, and relay 1129 remains normal. The operation of relay 1119 closes the operating circuit for relay 1121 which operates and starts the cycle of operation of relays 1122, 1124, 1123, 1125, 1126 and 1127 for the transmission of the four impulses for each digit of the office code as hereinbefore described in the transmission of the four impulses for the numerical digits.

In accordance with the office code established at the operator's position, the corresponding office code registers are operated and like the numerical registers as were described in the call indicator type of call, the condition of these office code registers provide the necessary paths for the four impulses for each digit of the office code. As hereinbefore explained the office registers operated when key No. 9 representing the first digit, was depressed, were 830 and 831, when key No. 9 for the second digit was depressed, the corresponding registers 820 and 821 were operated and when key No. 7 for the third digit was depressed the corresponding registers 810 and 812 were operated.

When relay 1115 releases, a circuit is closed for the transmission of the first impulse over the trunk extending to the tandem office, the circuit being traceable from battery, through the high resistance 828, conductor 927, right contact of relay 830, inner right back contact of relay 835, conductor 829, right front contact of relay 1102, outer right contact of relay 1114, left back contact of relay 1126, upper normal contact of relay 1125, tip side of the trunk,

through the windings of two polarized relays and one marginal relay arranged as a dry bridge in the sender circuit at the tandem office, ring side of the trunk, lower normal contact of relay 1125, inner left front contact of relay 1114, to ground at the lower front contact of relay 1107. The current for this impulse will be light positive and will be transmitted over the ring side of the trunk. The operation of relay 1125 reverses the current and inasmuch as relay 1127 has not as yet operated, a circuit is closed to transmit a heavy negative impulse over the ring side of the trunk, the circuit being traceable from battery, low resistance 827, conductor 929, right contact of relay 831, outermost left contact of relay 834, conductor 936, right back contact of relay 1127, conductor 937, lower-most front contact of relay 1125, ring side of the trunk, across the dry bridge at the tandem office, tip side of trunk, upper front contact of relay 1125, inner left front contact of relay 1114, to ground at relay 1107.

When relay 1125 deenergizes, in this cycle of operations, it again reverses the current in the trunk circuit, but inasmuch as relay 1126 has become operated, at the beginning of the second impulse, or period, and is maintained in this condition during the third impulse, or period, the impulsing circuit is therefore open and no current is transmitted for the third period.

When relay 1125 operates for the fourth period, it effects another reversal of the current in the trunk circuit and the current for this period is a light negative, the circuit for this impulse being traceable from battery, through the high resistance 828, conductor 927, inner and outer lower front contacts of relay 1125, ring side of the trunk, over the dry bridge at the tandem office, tip side of the trunk, upper front contact of relay 1125, inner left front contact of relay 1114, to ground at relay 1107. The fourth impulse completes the setting of the registers for the first digit of the office code in the sender at the distant office.

At the beginning of the third impulse, or period, relay 1124 operates for the second time, closing thereby an operating circuit for relay 835, the circuit being traceable from ground at relay 1124, outer right contact of relay 1126, conductor 918, right contact of relay 834, through the winding of relay 835, to battery. Relay 835 operates and opens the original operating circuit for relay 834 but relay 834 is maintained in an operated condition by its locking circuit hereinbefore described. The opening of the original operating circuit for relay 834 removed the shunt around relay 1129 and the latter relay operates. When relay 835 operates it prepares an operating circuit for cut-in relay 824, but inasmuch as relay 1129 is in an

operated condition, the operating circuit for relay 824 is opened and relay 824 cannot operate at this time. As hereinbefore explained, the cut-in relays are not permitted to operate until all the impulses of the preceding set have been transmitted and the means for preventing such operation is accomplished by maintaining relay 1119 operated until the fourth impulse of the preceding set has been sent.

The sets of impulses for the second and third digits of the office code are transmitted to the tandem office and the transmission of each set are regulated and controlled by relay 1119 which momentarily releases at the end of each period. At the end of the fourth impulses for the third office code digit, relay 815 is in an operated condition and relay 1119 is normal so that both the original operating and the locking circuits for relay 1114 are opened. However, relay 1103, one of the class relays operated for this type of call, provides a closure for the holding circuit for relay 1114 and relay 1114 is maintained operated, the holding circuit being traceable from battery through the winding of relay 1114, right front contact of relay 1103, conductor 1133, left back contact of relay 951, conductor 917, outer front contact of relay 914, conductor 908, right contact of relay 1113, left back contact of relay 1116, to grounded conductor 1104. The operated condition of relay 815 also prepared a circuit for the operation of cut-in relay 915 and the operation of the latter relay is effective when relay 1119 operates at the beginning of the fourth period or the set of impulses for the first numerical digit of the called subscriber's number. The sets of impulses for the four numerical digits are transmitted to the sender in the tandem office in the same manner as hereinbefore described in the call through the call indicator equipment.

A call through a tandem office; where the office code is recorded in a tandem sender and a numerical code is recorded in and sent direct to the terminating office by the sender in the originating office.

If it is desired to complete the call through a tandem office in which case the office code of the call subscriber's number is recorded in the tandem sender for the purpose of selecting an idle trunk extending to the terminating office and the numerical code is recorded in the sender at the originating office so that when the idle trunk is connected, the call may be established direct by the sender at the originating office, the class circuit shown in Fig. 4 will cause the operation of relay 1102 of the impulsing circuit as hereinbefore described. In this type of call, the class relays 1101 and 1102 remain normal and relays 1106, 1108, 1113,

1107, 1114, 1115 and 1119 are subsequently operated as hereinbefore described and the operations of relays 1107 and 1119 effects the releases of relays 1108 and 1115 respectively. The cut-in relays 834, 824 and 814 and the sender advance relays 835, 825 and 815 are operated in their proper sequence as described for the preceding type of call and the three sets of impulses for the office code digits are transmitted accordingly to the tandem sender. The tandem sender then hunts and selects an idle trunk in the desired group.

Inasmuch as relay 1103 is normal as stated above, relay 1114, at the end of the third period for the office code impulses, releases when its operating and locking circuits are open at the outer left contact of relay 815 and the outer right contact of relay 1119 respectively. The release of relay 1114 closes an operating circuit for relay 1116, the circuit being traceable from battery, through the winding of relay 1116, back contact of relay 1114, right back contact of relay 1103, right back contact of relay 1134, conductor 1135, left front contact of relay 815, to grounded conductor 1104. Relay 1116 operates and opens the operating circuit for relays 1107 and 1113, and the two last mentioned relays release. The operation of relay 1116 also closes an obvious relay 1134 which operates and locks, and prepares at its right front contact, a second operating circuit for relay 1114. The operation of relay 1134 also opens the operating circuit for relay 1116 which releases. The release of relay 1107 permits the test relay 1108 to again operate, should the line of the called subscriber connected to the elected trunk extending from the tandem office and the desired subscriber's line be idle. Relay 1108 operates and closes the energizing circuit for relay 1113 a second time. Relay 1113 operates as before and effects the operation of relay 1107, and relay 1108 consequently releases. The second operating circuit for relay 1114 is now closed by the release of relay 1116 and the operation of relay 1113 and the circuit may be traced from battery through the winding of relay 1114, right front contact of relay 1134, conductor 1133, left back contact of relay 951, thence over the same path as the first operating circuit. Relay 1114 operates and the further operation of the impulsing circuit as described in the transmission of the impulses for the call through the call indicator equipment, is repeated.

Completion of the connection.

When all the impulses necessary to complete the desired call have been transmitted over the seized trunk the operator shall, if she has not already done so, insert the calling end of cord 1015 into jack 1016 which

it is assumed corresponds to the number displayed at the switchboard and which is connected to the seized trunk 1011. Sleeve relay 1020 operates and connects ground to conductor 1024 for the purpose of operating relay 511 should a second trunk in this group be desired while trunk 1011 is busy as hereinbefore stated. Relay 1020 also closes a circuit extending through the windings of relays 1025 and 719 and the circuit may be traced from battery, through the winding of relay 1025, right contact of relay 1020, conductor 1026, operated contact sets 1029 and 1022, conductor 1027, through the high resistance right hand winding of relay 719, to ground at the middle armature of relay 712. Relay 719 operates, but relay 1025 being marginal remains normal inasmuch as the circuit extends through the high resistance winding of relay 719. The operation of relay 719 opens the holding circuit for relay 708 and inasmuch as the original operating circuit for relay 708 which extended through left hand high resistance winding of relay 708 was open when relay 944 was operated, relay 708 deenergizes. The release of relay 708 effects the release of relays 240, 211 and 153 and magnet 239. The release of magnet 239 causes position finder switch 200 to return to normal. The operation of relay 719 opens the locking and the operating circuits for relays 119, 129 and 137, and 141, 142 and 143, respectively which deenergize thereby effecting the release of relays 145, 149 and 154. The release of relay 145 opens the locking circuit for relay 602 and the release of relay 153 opens the locking circuit for the operated relay. The trunk indicator circuit is therefore opened and the associated lamp which displayed the number of the seized trunk is extinguished.

When the impulses for the units digit of the called subscriber's number are being transmitted and relay 957 is operated, an operating circuit for relay 1120 is prepared and the latter relay is operated when the cycle of operations of the impulsing circuit reaches, subsequent to the operation of relay 957, the point where relay 1129 is normal and relay 1119 is off normal, the circuit being traceable from battery, through the winding of relay 1120, conductor 1136, inner right front contacts of relay 957, 955, 953 and 951, left back contact of relay 1102, contact of relay 1129, conductor 1128, to ground on relay 1119. This circuit is effective in those classes of calls where relay 1102 remains normal, but in those classes where relay 1102 is energized, the operating circuit will be closed in a path extending over the outer right front contacts of relays 815, 825 and 835 and outer left front contact of relay 1102. Inasmuch as relay 1123, one of the cycle relays of the impulsing circuit,

is in an operated condition at the time relay 1120 operates an operating and a locking circuit is closed for relays 720 and 719, respectively, the locking circuit extending through the low resistance left hand winding and the front contact of relay 719, back contact of relay 708 and the operating circuit extending from battery, through the winding of relay 720, and then both circuits extending over conductor 722, left front contact of relay 1120, to ground at the outer right front contact of relay 1123. Relay 1120 operates and closes an obvious locking circuit for itself and relay 719 shunts its high resistance right hand winding and effects the operation of the marginal relay 1025. The operation of relay 1025 connects the calling subscriber's line with trunk 1011 outgoing to the distant office and inasmuch as the sender has completed the transmission of the necessary impulses, as explained above, ringing current is applied automatically to the called subscriber's line. Relay 1025 locks over its front contact in a circuit extending to ground at the left contact of sleeve relay 1120 and this locking circuit maintains relay 1025 in an operated condition as long as the calling end of the cord is connected to jack 1016. The operation of relay 1025 opens the operating circuit of relay 712 which deenergizes thereupon releasing the sender, impulsing circuit, panel registers shown in Fig. 12, and relay 1127 in the panel revertive pulse count circuit. The operation of relay 1025 also opens the holding circuit for magnet 1002 which releases and permits the trunk selector switch 1000 to restore the contact sets 1022 and 1029 to normal, but the link 1008 is not available for another connection until relay 1020 deenergizes.

The final operations necessary for establishing the connection for conversation and for restoring the operated apparatus at the closure of the conversation is accomplished in the regular way.

Should for any reason the operator decide to abandon a call prior to inserting the calling end of the cord into the seized trunk jack and fail to wipe out the connection so far established, the alarm lamp 543 would light, indicating that the marker and position equipment is held in an operated condition. The operator would then operate her wipe out key 157 and the connection would be opened. The lamp is arranged to be lighted by the operation of relay 506 which operates at the end of the interval usually allowed for the release of the marker in a properly established call.

For a more detailed description of a system in which switches of the panel type are controlled by senders involving counting relays and registers, reference is made to the patent to F. A. Stearn No. 1,501,871, granted

July 15, 1924. This patent also shows the details of a call indicator circuit such as described in this specification.

For a detailed description of a system employing switches of the coordinate type involving interoffice marking as related herein, reference is made to the patent to S. B. Williams No. 1,517,331, issued December 2, 1924, and to the application of S. B. Williams and E. S. Gibson, Serial No. 645,011, filed June 13, 1923, patent No. 1,543,967, issued June 30, 1925.

With regard to the general purpose and functioning of a key indicator system as well as the details of operation, reference is made to the patent to L. M. Allen No. 1,513,362, issued October 28, 1924.

What is claimed is:

1. In a telephone system, an operator's position, trunks leading from said position, selectively operable apparatus in which said trunks terminate, an operator's controlling mechanism, a primary registering and controlling device, a secondary registering and controlling device, a switch for associating said operator's controlling mechanism with said primary registering and controlling device, a second switch for associating said operator's controlling mechanism with said secondary registering and controlling device, means for causing the registration of designations in both primary and secondary registering and controlling devices, means controlled by said primary registering and controlling device in accordance with its registered designation to select one of said trunks, means controlled by said secondary registering and controlling device to operate the selectively operable apparatus associated with the selected trunk, and means for identifying said trunks to the operator.

2. In a telephone system, an operator's position, groups of trunks leading from said position, selectively operable apparatus in which said trunks terminate, an operator's controlling mechanism, a primary registering and controlling device, a secondary registering and controlling device, a switch for associating said operator's controlling mechanism with said primary registering and controlling device, a second switch for associating said operator's controlling mechanism with said secondary registering and controlling device, means for causing the registration of designations in both primary and secondary registering and controlling devices, means controlled by said primary registering and controlling device in accordance with its registered designation to select an idle trunk in a desired group, means controlled by said secondary registering and controlling device to operate the selectively operable apparatus as-

sociated with the selected trunk, and means for identifying said trunks to the operator.

3. In a telephone system, an operator's position, trunks leading from said position, selectively operable apparatus in which said trunks terminate, an operator's controlling mechanism, a primary registering and controlling device, a secondary registering and controlling device, a switch for associating said operator's controlling mechanism with said primary registering and controlling device, a second switch for associating said operator's controlling mechanism with said secondary registering and controlling device, means for causing the registration of designations in both primary and secondary registering and controlling devices, means controlled by said primary registering and controlling device in accordance with its registered designation to select one of said trunks, means controlled by said secondary registering and controlling device to operate the selectively operable apparatus associated with the selected trunk, means for identifying said trunks to the operator, and control circuits for said last mentioned means extending through contacts of said first switch.

4. In a telephone system, an operator's position, groups of trunks leading from said position, switches in which said trunks terminate, a sender, a controlling marker common to all of said groups of trunks, means controlled by the operator for causing the registration of a designation in said marker, means for selectively connecting said marker in accordance with the designation recorded therein to the trunks of any group, said marker including a series of test relays for testing the individual trunks of the group to determine an idle one, means controlled by the sender for operating the switch associated with the selected idle trunk, and means at the operator's position for identifying said trunks.

5. The combination in a telephone system of an operator's position, groups of trunks of different classes outgoing therefrom, switches in which said trunks terminate, a sender, a marker, means controlled by the operator for establishing designations in said marker pertaining to said groups of trunks, means controlled by the marker in accordance with the designations established for selecting a group of said trunks and for connecting the sender to an idle trunk in said group, said sender being adapted to control the switches to which said trunks lead, and means for indicating to the operator the designation of said trunks.

6. The combination in a telephone system of an operator's position, groups of trunks of different classes outgoing from said position, selectively operable devices of differ-

ent types in which said trunks terminate, a register sender, a controlling marker, means controlled by the operator for establishing the record of a designation in said 5 marker, means controlled by the marker for selecting a desired group of trunks and for choosing an idle one therein, said sender being adapted to control any one of said switching devices over the associated trunk 10 when selected, and means for identifying the selected trunks to the operator.

7. In a telephone system, an operator's position, a switchboard thereat, trunks appearing in said board and designated in a 15 definite order, a register controlling mechanism, means controlled by the operator for

establishing the record of a designation in said mechanism, a register sender, a switch for connecting said sender to said trunks, said trunks appearing in the switch in any 20 desired order, means controlled by said mechanism for selectively operating said switch, means included in said mechanism for identifying the position of the selected trunk in said switch, and indicating means 25 controlled by said last mentioned means for indicating to the operator the position of the selected trunk in said switchboard.

In witness whereof, I hereunto subscribe my name this 25th day of February, A. D., 30 1925.

EDWARD E. HINRICHSEN.
